UNITED STATES PATENT OFFICE.

JOHN EDWARD ALDRIDGE, OF HUNTINGTON, WEST VIRGINIA.

JAR-LIFTER.

1,274,229.

Specification of Letters Patent. Patented July 30, 1918.

Application filed January 15, 1918. Serial No. 211,973.

To all whom it may concern:

Be it known that I, JOHN E. ALDRIDGE, a citizen of the United States, residing at Huntington, in the county of Cabell and State of West Virginia, have invented certain new and useful Improvements in Jar-Lifters, of which the following is a specification.

This invention relates to jar lifters, and 10 more particularly to an instrument for lifting fruit or preserving jars out of the water in which they are sterilized during the canning or preserving process.

One of the main objects of the invention 15 is to provide a device of the character stated of simple construction and operation which may be produced at relatively small cost. A further object is to provide a device which may be quickly and easily secured about the 20 threaded neck of a jar of the Mason type now commonly used so as to grip the jar and permit it to be lifted or tilted as desired. A further object is to provide a device having two gripping jaws adapted to 25 fit about the neck of a jar, these jaws being oppositely disposed and normally held apart. A further object is to provide simple and efficient means for forcing the gripping jaws toward each other and for securing 30 them against relative movement, so as to grip the neck of a jar or container. Further objects will appear from the detailed description.

In the drawings:

35 Figure 1 is a side view of a lifter constructed in accordance with my invention.

Fig. 2 is a section taken substantially on line 2—2 of Fig. 1.

Fig. 3 is a section taken on line 3—3 of 40 Fig. 1.

The head or handle of the lifter is constructed of wood or other suitable material which does not readily conduct heat. Within this head are secured the upper ends of 45 the gripping members. These members are each formed by bending from a continuous piece of resilient wire or other suitable material. Each gripping member is provided with the parallel shanks 2 and 3 the upper 50 ends of which are secured in head 1. Shank 2 is turned outwardly to produce an integral horizontal arm 4 then downwardly to provide a connecting bar 5, the material being then bent upwardly and inwardly to provide 55 a short connecting bar 6, after which the material is bent outwardly to provide a sub-

stantially semi-circular gripping jaw 7, the other end of this jaw being connected to shank 3 by a short rod 6^a, rod 5^a, and bar 4^a. By shaping the gripping members in this manner, I provide, in effect, two substantially rectangular frames which are movable toward and away from each other, these frames being provided with horizontally disposed oppositely directed arcuate gripping jaws 7 which are of substantially semi-circular shape. The shanks 2 and 3 of the gripping members are set in the head 1 so as to diverge downwardly beyond the head, the object of this being to normally hold the gripping jaws 7 away from each other thus providing an opening of sufficient size to readily receive the usual threaded neck of a fruit jar or similar container.

In using this device, this gripping head 75 which is composed of the jaws 7 and the connecting bars, is placed about the neck of the container and jar so as to bring the jaws 7 into engagement with the usual annular shoulder adjacent the base of the neck. A 80 locking ring 8 which is slidably mounted on the shanks of the gripping members for this purpose, is then forced downwardly of the shanks so as to force them toward each other, thus bringing the gripping jaws 7 85 into engagement with the neck of the jar beneath the lowermost thread. When the jar is thus gripped, it may be readily lifted or tilted. The wire or other material from which the gripping members are made, 90 should have sufficient rigidity to permit tilting of the jars when filled with hot water during the sterilizing process preliminary to canning so as to empty the water from the jar without bending or distortion of these 95 members. After the cover has been placed upon the jar, the food to be canned having been placed in the jar, the jaws 7 each grip under the usual rubber packing ring so as to firmly hold the jar and permit it to be lifted 100 from the sterilizing bath in the usual manner. By means of this device it is possible to handle a jar during the various stages of the canning process without the user being in danger of scalding her hands, as frequently happens when it is attempted to handle the jars directly by hand.

It will be evident that there may be slight changes made in the construction and arrangement of the different parts of my invention without departing from the field and scope of the same, and I intend to include

all such variations, as fall within the scope of the appended claims, in this application in which a preferred form only of my invention is disclosed.

5 What I claim is:

1. In a device of the character described, two gripping members comprising spaced shanks disposed in downwardly divergent relation, said shanks being resilient, oppositely directed approximately semi-circular gripping jaws carried by said shanks at the lower ends thereof and movable toward and away from each other, and means for forcing said jaws toward each other and for readily securing them in gripping relation.
- 10 2. In a device of the character described, a handle, and two opposed gripping members secured in said handle in downwardly divergent relation, each of said gripping members being formed from a length of

wire bent to provide two substantially parallel shanks having their upper ends secured in the handle, the lower portion of each of these shanks being turned outwardly and downwardly to form a substantially rectangular vertically disposed frame, the portion of the wire intermediate the ends of this frame being then bent to provide a substantially semi-circular gripping element, the gripping elements of the two said gripping members being opposed and adapted to fit about the neck of a jar or similar container.

25 30 In testimony whereof I affix my signature in presence of two witnesses.

JOHN EDWARD ALDRIDGE.
